UNITED STATES PATENT OFFICE.

ELIAS JONES HALE, OF FOXCROFT, MAINE.

BURNER FOR LAMPS.

SPECIFICATION forming part of Letters Patent No. 285,028, dated September 18, 1883.

Application filed July 17, 1883. (No model.)

To all whom it may concern:

Be it known that I, ELIAS JONES HALE, of Foxcroft, in the county of Piscataquis, of the State of Maine, have invented a new and useful Improvement in Burners for Lamps; and I do hereby declare the same to be described in the following specification and represented in the accompanying drawings, of which—

Figure 1 is a top view, Fig. 2 a bottom view, Fig. 3 a side elevation, and Fig. 4 a transverse section, of a lamp-burner of my improved kind as it appears without its cone. Fig. 5 is a top view, and Fig. 6 a side elevation, of the cone. Fig. 7 is a transverse section of the burner, having the cone in place thereon. Fig. 8 is a top view of a duplex wick holder or tube made of a single piece of metal, such a tube or holder being shown in Figs. 1 and 3.

20 This burner has two wicks arranged in parallelism with each other, and having each of them extended, at one edge of it, beyond the next adjacent edge of the other without lapping thereon, all being substantially as set forth.

25 The burner also has its cone revoluble a short distance relatively to the wicks, and provided with a horn or projection extended from it down through a slot in the chimney-holder, such horn or projection being to enable a person, by taking hold of it when the chimney is

30 in place on the supporter, to turn or revolve the cone to adjust it relatively to the wicks to cause the flame to rise more or less at its middle, as occasion may require. The object of 35 the two wicks arranged with reference to each other, as described, and having to each a separate elevator, is to enable either to be raised in altitude or adjusted with respect to the other to prevent a flame from them from "forking,"

40 or rising at one edge higher than at the other. The burner has a holder or chamber for each wick, and to each holder or chamber a wick-elevator. These chambers may be in two

45 separate tubes, or may be formed by a single piece of metal, bent in manner as shown in end view in Fig. 8, and soldered at its opposite edges, *a b*, to the median part *c*; or such wick-chambers may be in a single tube made in transverse section, as shown in Fig. 9, in

50 which case the two wicks would generally be

in contact, each extending beyond the other edgewise thereof.

In the drawings, *A* denotes the foraminous supporter for the chimney and the cone, such supporter being concentric with and fastened to the wick-tube supporter *B*, through which the wick tube or tubes extend, as shown at *C*, such tube or tubes being to carry two separate wicks, *D E*, arranged in parallelism with each other, and each extended at one edge of it beyond the next adjacent edge of the other without lapping thereon. To each wick there is a separate elevator, *F*, having its shaft *c* properly applied to the wick-tube supporter, and extended therefrom and provided with a milled head, *d*, as represented. By means of its elevator either wick can be adjusted in altitude relatively to the other, so as to prevent a flame from it from forking or "pointing" or becoming pointed more or less at one edge of it. By having two flat wicks arranged as explained the flame formed by them can be made in its light-giving property nearly if not quite as effective as that of a single wick having a width equal to those of both of the said wicks. Besides, a wick-tube supporter of less size or diameter can be used than would be required for a single wick-tube to carry a wick having a width double that of either of the two wicks.

55 60 65 70 75 80 85 90 95 100
The cone *G*, supported in a circular recess in the chimney-supporter, has a horn or finger, *f*, extending down from it through an arcal slot, *g*, made in the supporter. By taking hold of the said horn or finger when the glass chimney is in place on its supporter a person can turn the cone more or less, so as to change the position of the air-educt of it, or bring it more or less oblique to the wick or wicks, to cause the flame therefrom to rise at its middle or spread laterally, as occasion may require.

I claim—

1. A lamp-burner provided with two flat wicks arranged side by side or in parallelism, and each extended at one edge of it beyond the next adjacent edge of the other without lapping thereon, all being substantially as set forth, each of such wicks being movable lengthwise in its tube or holder.

2. A lamp-burner provided with two wick-

holders or chambers arranged in parallelism, and each extended at one edge of it beyond the next adjacent edge of the other without lapping thereon, all being substantially as shown and described.

3. A lamp-burner having its cone revoluble on its supporter, as explained, relatively to the wick or wicks, and provided with a projection or horn extended down from it (the

said cone) through a slot in the supporter, whereby a person taking hold of such horn can turn the cone more or less for the purpose set forth, while the chimney may be in place on the supporter.

ELIAS JONES HALE.
